Primary Examiner — Mark Goodwin(74) *Attorney, Agent, or Firm* — Carlson, Gaskey & Olds, P.C.(57) **CLAIM**

The ornamental design for a hand loom for forming brunnian link articles, as shown and described.

DESCRIPTION

FIG. 1 is a perspective view of a hand loom for forming brunnian link articles showing my new design;

FIG. 2 is a side view thereof, all other sides being identical thereof;

FIG. 3 is a top view thereof; and,

FIG. 4 is a bottom view thereof.
